UNITED STATES PATENT OFFICE.

ARTHUR R. HAVENER, OF WALTHAM, MASSACHUSETTS, ASSIGNOR TO JUDSON L. THOMSON M'FG CO., A CORPORATION OF MASSACHUSETTS.

TRUNK-RIVETING MACHINE.

1,031,260.

Specification of Letters Patent. Patented July 2, 1912.

Application filed May 15, 1911. Serial No. 627,206.

To all whom it may concern:

Be it known that I, ARTHUR R. HAVENER, a citizen of the United States, residing at Waltham, in the county of Middlesex and 5 State of Massachusetts, have invented new and useful Improvements in Trunk-Riveting Machines, of which the following is a specification.

This invention relates to a machine for 10 riveting strips of sheet material to trunks and the like.

The object of the invention is to provide a cheap, simple and easily operated machine for fastening strips of sheet material to the 15 corners of trunks or for fastening such strips to the sides of trunks intermediate the corners.

The invention consists in the combination and arrangement of parts set forth in the 20 following specification and particularly pointed out in the claims thereof.

Referring to the drawings: Figure 1 is a side elevation of my improved riveting machine, the same being partly broken away 25 and shown in section. Fig. 2 is a front elevation of the same. Fig. 3 is a sectional elevation enlarged taken on line 3—3 of Fig. 1. Fig. 4 is a sectional plan taken on line 4—4 of Fig. 2. Fig. 5 is a sectional elevation taken on line 5—5 of Fig. 2, looking toward the left in said figure and a portion of a trunk being illustrated together with the strip riveted thereto. Fig. 6 is a sectional elevation taken on line 6—6 of Fig. 35 5 looking toward the left in said figure. Fig. 7 is a sectional plan taken on line 7—7, Fig. 5, showing the style of presser foot used when a corner strip is being riveted to the trunk. Fig. 8 is a sectional plan similar 40 to Fig. 7 illustrating the presser foot which is used when the strip is being riveted intermediate the corners of the trunk. Fig. 9 is an enlarged sectional elevation illustrating a portion of a trunk on the work-support 45 and the presser foot in position to hold a corner strip on said trunk, together with the rivet holder and driver and coacting parts, the driver and rivet holder being shown in their uppermost positions, all as viewed from 50 the front of the machine. Fig. 10 is a sectional elevation similar to Fig. 9 taken on line 10—10 of Fig. 5, the driver and rivet holder being shown in their lowermost posi-

tions. Fig. 11 is a vertical sectional elevation of a modified form of work-support and 55 trunk feeding mechanism. Fig. 12 is a plan, partly in section, of the horizontal lever and actuating mechanism which are illustrated in Fig. 11, the lever being broken away to save space in the drawings. 60

Like numerals refer to like parts throughout the several views of the drawings.

In the drawings, referring to Figs. 1 to 10, inclusive, 15 is the frame of the machine consisting of a head 16 and a base 17. The 65 trunk or other work to be operated upon is supported upon a work-support 18 which consists of a bracket having a horizontal arm 19 and a vertical arm 20. The arms 19 and 20 are hollow and are each closed at one 70 side thereof by plates 21 and 22, respectively. An anvil 23 is mounted in the upper end of the vertical arm 20 of the work-support 18. The trunk 24 rests upon the upper end of the vertical arm 20 of the work-support and 75 is fed therealong by a feed lever 25 which terminates at its upper end in a feed finger 26 fast to said feed lever and forming, in effect, a portion thereof. The feed finger 26 is slotted at 27 to receive the cross-bar 28 of 80 the upper end of the work-support and the arms 29, 29 of the bifurcated portion of said feed finger are provided with corrugations or teeth 30 upon their upper edges which bear against the under surface of the trunk 85 24 during the feeding operation. The feed lever 25 (Fig. 4) is slidably mounted upon a block 31 which, in turn, is pivoted on a stud 32 which is adjustable longitudinally of the vertical arm 20 and is clamped thereto by means of a nut 33 which has screw-threaded engagement with the stud 32. The stud 32 terminates at one end thereof in a projection 34 which projects into a slot 35 in the plate 22, and adjacent to the slot 35 90 is a series of lines forming a scale numbered from 0 to 60 which indicates the length of feed imparted to the feed finger 26 when the projection 34 is in line with these different lines of the scale, (Fig. 1). 100

A combined rocking and longitudinal motion is imparted to the lever 25 by a lever 36 which is connected thereto by a pin 36' and said lever 36 is slidably longitudinally thereof upon a block 37, said block being pivoted 105 to a stud 38 fast to the horizontal arm 19.

A combined longitudinally reciprocating and rocking movement is imparted to the lever 36 by an eccentric 39 fast to a shaft 40 journaled to rotate in bearings 41, 41 in the base 17 (Figs. 1 and 2). The shaft 40 is rotated by a gear 42 fast thereto and meshing into a bevel gear 43 fast to a vertical shaft 44 which is journaled in bearings 45, 46 in the base and head 17 and 16, respectively. A bevel gear 47 is fast to the upper end of the shaft 44 and meshes into a bevel gear 48 which is fast to the main driving shaft 49. The main driving shaft 49 is journaled in bearings 50, 50 in the head 15 of the machine and is rotated by a clutch pulley 51 (Fig. 2).

The rivets which are to be driven into the trunk are placed in mass in a hopper 52, the rotary member of which is driven by a belt 20 53 and pulley 54, said pulley 54 being fast to the shaft 49. The rivets pass from the hopper 52 down a raceway 55 to a separator slide 56, which separator slide is operated to feed the rivets one by one to the lower portion 25 57 of the raceway 55 by a lever 58 pivoted at 59 to the head 16 and rocked in one direction by a spring 60 and in the other direction by a projection 61 upon a link 62 to which a reciprocatory motion is imparted 30 as hereinafter described. The rivets pass one by one in a manner well known to those skilled in the art from the lower portion 57 of the raceway into a rivet holder 63. This rivet holder is made in two parts 64, 64, 35 each supported upon a spring arm 65 which is fastened to a slide 66. The slide 66 is guided in ways 67 in the head of the machine.

The driver 68 is fast to a driver bar 69 40 which is guided in ways 70 in the head of the machine and has a reciprocatory motion imparted thereto by a pair of toggle links 71 and 72. The link 71 is pivoted at 73 to the upper end of the driver bar 69. The link 72 is pivoted at one end thereof upon an eccentric 74 formed upon a stud 75 which is journaled to rotate in the head 16 (see Figs. 2 and 3). The stud 75 can be rotated and locked in different positions by 50 a handle 76 which carries a spring-actuated locking pin 77 adapted to be forced by the spring 78 into any one of the holes 79, 79 in the locking plate 80 which is fastened to the head 16. The links 71 and 72 are connected by a pin 81 to the link 62, the other end of said link 62 being pivoted to a crank-pin 82 fast to a disk 83 which, in turn, is fastened to the shaft 49. Thus, by the rotation of the crank-disk 83 and its crank-pin 60 82 a reciprocatory motion is imparted to the link 62 which, in turn, rocks the links 72 and 71 upon their pivots 74 and 73, respectively, thus imparting a reciprocatory motion to the driver bar 69 and to the driver 68.

The rivet holder slide 66 is moved upwardly in its ways 67 by a spring 84 (see Fig. 1). It is moved downwardly by the driver bar 69 which is adapted to engage a pin 85 as said driver bar descends (see 70 Figs. 9 and 10). The pin 85 is mounted to slide transversely of the rivet holder slide 66 and has a reciprocatory motion imparted thereto transversely of said slide by a lever 86 pivoted at 87 to said slide. The lever 86 75 has an arm 88 thereon which projects downwardly into a slot 89 in the pin 85.

When the parts are in the position illustrated in Fig. 9, it will be seen that the pin 85 is held in such position that it will be 80 engaged by the driver bar 69 as said driver bar descends. This will carry the rivet holder downwardly, together with the rivet holder slide 66, until the portion 90 of the lever 86 engages the top of a stationary stop 91, when said lever 86 will be tipped, by its engagement with the stop, from the position illustrated in Fig. 9 relatively to the slide 66 to that illustrated in Fig. 10, the head or flange 92 upon the stop 91 entering at 90 this time a notch 93 in the lever 86, and the lever being tipped upon its pivot will move the locking pin 85 out of engagement with the driver bar 69, which will then continue its downward movement until it has driven 95 the rivet out from between the two spring-supported sides of the holder 63 and through the strip 94 and the side of the trunk 24, and has clenched the rivet 95 against the anvil 23. Upon the reverse motion, when the driver bar 69 is moved upwardly sufficiently to clear the right hand end of the pin 85 (Fig. 10) a flat spring 96, which bears against the outer end of the pin 85, will drive said pin forward or to the 100 right (Fig. 10), to the position illustrated in Fig. 9, thus disengaging the lever 86 from the head 92 of the stop 91 and allowing the rivet holder slide 66 to be moved upwardly by its spring 84.

When a corner piece 94 is being fastened to the trunk 24, as illustrated in Fig. 10, it is held firmly in position against the outer surface of the trunk by a presser foot of the style illustrated in Figs. 7 and 10, in which the presser foot 97 has an angle plate 98 at the bottom thereof which bears against the top and side of the corner piece 94, as clearly seen in Fig. 10. This angle plate 98 is clamped to the lower end of a sleeve 99 by a nut 100 which has screw-threaded engagement with a projection 101 at the lower end of the sleeve 99. The sleeve 99 is mounted to slide vertically upon a stud 102 which, in turn, is adapted to slide within a vertical recess 103 in the head 16 of the machine (see Fig. 5). A spring 104 encircles the sleeve 99 and bears at its lower end against a flange 105 upon said sleeve, while at its upper end it bears against a cross-pin 106 which is fast 108

to the sliding stud 102 and projects through slots 107 in diametrically opposite sides of the sleeve 99. The sliding stud 102 may be moved upwardly or downwardly by means 5 of a lever 108 which is connected to said slide by a pin 109 and is pivoted at 110 to the head of the machine. Upon the lever 108 is mounted a locking latch 111 which is pivoted at 112 to the lever 108, one end of said 10 latch 111 being provided with a notch 112' adapted to engage a rib 113 upon the head of the machine. A spring 111' holds the free notched end of the locking latch 111 in engagement with the rib 113 when the parts 15 are in the position illustrated in Fig. 9, thus locking the presser foot downwardly and clamping the corner piece 94 to the trunk 24 it being understood that while in this position the spring 104 will yield slightly 20 during the feeding of the trunk along beneath the presser foot plate 98.

The presser-foot plate illustrated in Fig. 8 is substantially the same as that illustrated in Fig. 7 as to the manner in which 25 it is supported and actuated, but differs therefrom in that it is slotted upon its under side to straddle a flat strip 114, as seen in Fig. 8, the portions 115, 115 of said presser foot extending down and along the 30 opposite edges of the strip 114 and thus forming a guide for said strip as it is being riveted to a portion of the trunk intermediate the corners.

The general operation of the mechanism hereinbefore specifically described is as follows: The trunk 24 is placed with one corner thereof resting upon the vertical arm 20 of the work-support 18 as illustrated in Figs. 5 and 10. The operator places the 35 corner strip 94 on the corner of the trunk and lowers the presser foot to the position illustrated in Figs. 9 and 10 and clamps the same in that position by forcing the lever 108 downwardly until the notched portion 40 112' of the locking latch 111 drops in beneath the rib 113 on the head of the machine, as illustrated in Fig. 9. He then throws the clutch into operation by means 45 of a treadle (not shown in the drawings) 50 which operates a rod 116 (Fig. 1), this rod, in turn, operating a clutch lever 117. The clutch pulley 51 is thus locked to the shaft 49 and rotates the same, causing the driver bar 69 to be moved downwardly by the links 55 62, 71 and 72, and as said driver bar moves downwardly with its driver, it carries with it the rivet holder 63, with one of the rivets 59 65 therein, until the under side of the rivet holder nearly touches the upper surface of 70 the strip 94. At this time the portion 90 upon the lever 86 will engage the flange 92 upon the stop 91 and throw the locking pin 85 out of engagement with the driver bar 69 and the flange 92 will project into the 75 notch 93 upon said lever 86 and the down-

ward motion of the rivet holder and the slide 66 will be stopped. The downward movement of the driver bar 69 and the driver 70 75 80 85 90 95 100 105 110 115 120 125 128 bar, however, continue and the rivet will be driven out from between the two sides of the rivet holder, down through the angle piece 94 and through the side of the trunk until the ends of the bifurcated rivet are turned by the anvil and clenched upon the inner surface of the trunk 24. As the driver bar moves up from the position illustrated in Fig. 10 toward that illustrated in Fig. 9, the lower end of the driver bar will pass upwardly above the pin 85 and said pin, then being released will be moved forward or toward the right (Fig. 10) by the flat spring 96 and will thus free the lever 86 from the stop 91. After this has been accomplished the spring 84 will act to carry the rivet holder slide 66 and the rivet holder thereon upwardly to its uppermost position as illustrated in Fig. 9. As soon as the driver bar starts up the trunk is fed forward by the lever 25 which is so timed as to be moved upwardly into engagement with the inner surface of the trunk and then to be moved toward the left (Fig. 1) to feed the trunk and strip forward in order to receive another rivet. The combined reciprocating and rocking movement is imparted to the lever 25 by the lever 36, eccentric 39 and shaft 40. The operation of alternately driving the rivet and feeding the trunk is repeated until the entire strip has been attached to the corner of the trunk, whereupon the operator stops the machine by releasing the treadle and throwing out the clutch.

It will be seen in the form of my invention illustrated in Fig. 1 that the trunk can be fed along the work-support toward the head 16 and base 17 only so far as the length of the horizontal arm 19 will allow and, therefore, for longer corners of the trunk another style of arm and mechanism for feeding said trunk is used, whereby said trunk, instead of being fed toward the head 16 and base 17, will be fed transversely thereof, the rest of the mechanism of the machine remaining the same and performing the same functions as hereinbefore described, and in Figs. 11 and 12 I have illustrated the modified form whereby it is possible to feed the trunk transversely of the head and base and transversely of the horizontal arm of the work-support. Referring then to Figs. 11 and 12 it will be seen that 18' is the work-support having a horizontal arm 19' and a vertical arm 20', the work-support being fastened to the base 17. The shaft 40' has a cam 118 fast thereto and working between the jaws 119, 119 on one end of a lever 120 which is pivoted upon a pin 121 fast to a block 122, the block 122 being, in turn, pivotally mounted upon a stud 123 fast to the arm 19'. 130

The cam 118 thus imparts a rocking motion to the lever 120 in a vertical plane and about the pivot 121. A rocking motion in a horizontal plane about the pivotal stud 123 is 5 also imparted to the lever 120 by a cam 124 which engages a cam roll 125 journaled upon the lever 120. The lever 120 is connected by a universal joint 126 to the lower end of a lever 127 which lever is slidable longitudinally thereof upon a block 129 which, in 10 turn, is pivoted upon a stud 128. The stud 128 is adjustably fastened to the vertical arm 20' by a nut 130, so that the lever 127 can slide longitudinally thereof upon the block 129 and can rock about the stud 128 as a pivot, thus imparting a compound four motion feed to the upper end of the lever 127 similar to that hereinbefore described with 15 relation to the lever 25, except that in this case the lever rocks in a plane extending transversely of the horizontal arm 19, whereas in the former case said lever rocked in a plane extending longitudinally of the arm 19. The operation of the machine 20 otherwise is the same, as to the driving and feeding of the rivets, in the form of my invention illustrated in Figs. 11 and 12 as in the form of my invention illustrated in 25 Figs. 1 to 10, inclusive.

It will be understood that the thickness 30 of the sides of the trunk 24 or of the corner strips 94 may vary, but that the inner face of the trunk will always occupy the same position relatively to the anvil and to the feed finger. Therefore, it follows that for 35 different thicknesses of trunk and strip, where different lengths of rivet are employed, in order to obtain the same clench of the rivet on the inner face of the trunk, 40 the point at which the lowermost end of the driver must stop and the point at which the lowermost end of the rivet holder must stop will vary. To compensate for this variation, the eccentric stud 74 is utilized to determine 45 the lowermost point at which the lowermost end of the driver will stop, said eccentric stud 74 being set and locked in different positions by means of the handle 76 and its locking pin 77, and the lowermost position 50 of the rivet holder is regulated by means of the stop 91 which has screw-threaded adjustment with a bracket 91' and is locked thereto by a set-nut 91''. If the thickness of the 55 trunk is greater in one case than another, then the stop 91 is screwed upwardly so that the pin 83 may be thrown out sooner and thus stop the rivet holder slide 66 and rivet holder 63 at a greater distance from the anvil or at a greater distance from the inner 60 face of the trunk which bears against the work-support. In the case of the driver bar and driver, if the thickness of the trunk is increased, then the handle 76 is moved upwardly or toward the right (Fig. 5), thus 65 raising the eccentric portion of the stud 74

and hence raising the lowermost end of the driver to correspond to the increased thickness of the trunk which is being riveted.

Having thus described my invention, what I claim and desire by Letters Patent to 75 secure is:

1. A machine for riveting strips of sheet material to trunks and the like, having, in combination, a work-support, an anvil on said work-support, a feed finger adapted to engage the face of a trunk which contacts with said work-support, mechanism adapted to impart a reciprocatory motion to said feed finger, a rivet holder, a driver, mechanism adapted to move said driver toward 80 and away from said anvil, and a presser foot adapted to bear against the upper face and an edge of each of said strips. 75

2. A machine for riveting strips of sheet material to trunks and the like, having, in combination, a work-support, an anvil on said work-support, a feed finger adapted to engage the face of a trunk which contacts with said work-support, mechanism adapted to impart a reciprocatory motion to said 85 feed finger, a rivet holder, a driver, mechanism adapted to move said driver toward and away from said anvil, and a presser foot adapted to bear against a single strip and having a recess in its under side adapted 90 to receive and guide said strip. 95

3. A machine for riveting strips of sheet material to trunks and the like, having, in combination, a work-support, an anvil on said work-support, a feed lever pivotally 100 and slidably mounted on said work-support, the upper end of said lever adapted to engage that face of a trunk which contacts with said work-support, mechanism adapted to impart to said lever a combined rocking 105 and longitudinal movement, a rivet holder, a driver, and mechanism adapted to move said driver toward and away from said anvil. 105

4. A machine for riveting strips of sheet material to trunks and the like, having, in combination, a work-support, an anvil on said work-support, a feed lever, a pivot upon 110 which said lever is slidably mounted, the upper end of said lever adapted to engage that face of a trunk which contacts with said work-support, mechanism adapted to impart to said lever a combined rocking and longitudinal movement, a rivet holder, a 115 driver, and mechanism adapted to move said driver toward and away from said anvil. 120

5. A machine for riveting strips of sheet material to trunks and the like, having, in combination, a work-support, an anvil on said work-support, a feed lever, a pivot ad- 125 justably fastened to said work-support upon which pivot said lever is slidably mounted, the upper end of said lever adapted to engage that face of a trunk which contacts with said work-support, mechanism adapted 130

to impart to said lever a combined rocking and longitudinal movement, a rivet holder, a driver, and mechanism adapted to move said driver toward and away from said 5 anvil.

6. A riveting machine having, in combination, a work-support consisting of a bracket having a vertical and a horizontal arm, an anvil at the upper end of said vertical arm, a feed lever pivotally and slidably mounted on said vertical arm, the upper end of said lever adapted to engage the material to be riveted, a lever pivoted on said horizontal arm of said work-support and connected to said feed lever, and mechanism adapted to impart to the lever on said horizontal arm a compound motion, whereby a combined rocking and longitudinal motion is imparted to said feed lever.

20 7. A riveting machine having, in combination, a work-support, an anvil, a driver bar and driver, a rivet holder, a slide to which said rivet holder is attached, and means adapted to alternately connect said 25 rivet holder slide to said driver bar and to disconnect said rivet holder slide from said driver bar.

8. A riveting machine having, in combination, a work-support, an anvil, a driver 30 bar and driver, a rivet holder, a slide to which said rivet holder is attached, a pin extending transversely of and adapted to connect said rivet holder slide to said driver bar, a lever pivoted to said rivet holder slide 35 and engaging said pin, and a stationary stop adapted to be engaged by said lever to move

said pin out of engagement with said driver bar.

9. A riveting machine having, in combination, a work-support, an anvil, a driver 40 bar and driver, a rivet holder, a slide to which said rivet holder is attached, means adapted to connect said rivet holder slide to said driver bar, and a stationary stop adapted to be engaged by a portion of said 45 connecting means to operate the same to disconnect said rivet holder slide from said driver bar.

10. A riveting machine having, in combination, a work-support, an anvil, a driver 50 bar and driver, a rivet holder, a slide to which said rivet holder is attached, a pin extending transversely of said rivet holder slide and adapted to connect the same and said driver bar together, a lever pivoted to said rivet holder slide and engaging said 55 pin, a stationary stop adapted to be engaged by said lever when said driver bar is moved toward said anvil to move said pin out of engagement with said driver bar, and yielding means adapted to move said pin into the path of said driver bar when said driver bar is moved away from said anvil, whereby said lever is rocked in the opposite direction.

In testimony whereof I have hereunto set 60 my hand in presence of two subscribing witnesses.

ARTHUR R. HAVENER.
